GOBLET OR SIMILAR ARTICLE

Frank J. Benes, Lancaster, Ohio, assignor to Anchor Hocking Glass Corporation, Lancaster, Ohio, a corporation of Delaware

Filed Apr. 30, 1968, Ser. No. 11,705

Term of patent 14 years

Int. Cl. D7—01

U.S. Cl. D36—8

FIG. 1 is an elevational view of a goblet or similar article showing my new design;

FIG. 2 is a bottom view thereof;

FIG. 3 is a sectional view taken along line 3—3 of FIG. 1;

FIG. 4 is a sectional view taken along line 4—4 of FIG. 1.

It is understood that the cut ornamentation shown fragmentarily in FIGS. 1 and 2 is continued about the entire goblet in the paths indicated.

I claim:

The ornamental design for a goblet or similar article, substantially as shown and described.
